INVENTOR.

OLAF BERG.

BY HIS ATTORNEY.

James F. Williamson

UNITED STATES PATENT OFFICE.

OLAF BERG, OF ST. PAUL, MINNESOTA.

OARLOCK.

Application filed September 27, 1924. Serial No. 740,251.

To all whom it may concern:

Be it known that I, OLAF BERG, a citizen of Sweden, residing at St. Paul, in the county of Ramsey and State of Minnesota, have invented certain new and useful Improvements in Oarlocks; and I do hereby declare the following to be a full, clear, and exact description of the invention, such as will enable others skilled in the art to which it appertains to make and use the same.

This invention has for an object to provide an extremely simple but highly efficient oarlock comprising few parts.

A further object of the invention is to provide an oarlock, one part of which will be permanently secured to the boat and the other parts of which will be carried by the oar, whereby the oar may be readily attached or detached, leaving no means on the boat whereby an ordinary oar may be substituted to propel the boat.

An additional object is to provide a reversible member on which the oar is mounted, which will permit the oar to be carried on the gunwale of the boat at two different levels.

It is a further object in such an oarlock to provide means whereby the oar cannot be thrown from the lock or out of the boat while rowing.

These and other objects of the invention will be apparent from the following description made in connection with the accompanying drawings, wherein like characters refer to similar parts throughout the several views, and in which,

Fig. 1 is a perspective view showing an oar and oarlock in working position on a portion of a rowboat;

Fig. 2 is a plan view showing a fragment of an oar with part of the oarlock carried thereby; and

Fig. 3 is a view partly in side elevation and partly in section of an oar in working position on a fragment of a boat equipped with the novel oarlock.

Referring to the drawings:—

The numeral 4 indicates a rowboat having a gunwale to which a pintle bracket 5, carrying an upstanding pintle 6, is secured. A cylindrical hub member 7 is adapted to be slipped over pintle 6 for horizontal pivotal motion thereon. A pin or bolt 8, preferably cast integral with the hub 7, projects therefrom at substantially 90 degrees to the axis

thereof, and is provided with a collar or flange 8^a adjacent the hub 7. The outer end of pin 8 is threaded to engage a nut 9. The invention requires the use of a specially prepared oar 10 having a transverse aperture 60 therethrough in which a bushing 11 is disposed adapted to form a bearing for pin 8, which passes therethrough and is secured thereto by the nut 9. Obviously, the oar 10 is capable of vertical pivotal motion on the pin 8 and horizontal pivotal motion on the pintle 6. The aperture in oar 10 is preferably made at right angles to the plane of the blade of the oar, whereby the blade will always be held in proper working position to 70 the water. A transverse aperture is provided in the top of the pintle 6 through which a cotter pin 12, flexibly secured to the hub 7 by the chain 13, may be passed to detachably lock the hub on pintle 6 with freedom for pivotal motion.

The pin 8 projects from the hub 7 at a point thereon considerably nearer one end thereof than the other end, enabling the oar to be set to two different levels by simply turning the hub upside down, and, as the opposite oarlocks will be rights and lefts, this change in levels can be made while keeping the oars in the same relative positions relative to the seat on which the oarsman sits, by shifting the oarlocks to opposite sides of the boat when the hubs are reversed. This adjustment of the level of the oar is of considerable importance, since, when rowing in rough weather, the oars should be "rigged" considerably higher or at a higher level than when the water upon which the boat is rowed is perfectly calm. The high rigging is necessary to enable the oarsman to get his oar in and out of the water without trouble, due to the waves at the side of the boat.

It is also obvious that the oarlocks may be readily adjusted for either pulling or pushing of the oars, or, in other words, the oar may be positioned nearer to or farther away from the oarsman by merely turning the hubs upside down without shifting from right to left pintles. In the usage of the oar, it is, of course, obvious that swinging motion in a horizontal plane is facilitated by the hub 7, while pivotal motion in a vertical plane is facilitated by the bearing through which the pin 8 passes. It will also be noted that the oar, itself, cannot be turned 110

in the lock but that the blade is always set at proper pitch for engaging the surface of the water.

The part of the lock carried by the boat, 5 namely, the pintle bracket, will not accommodate an ordinary oar or oarlock, so that when the oars are removed and the boat left, there will be little chance of a trespasser rowing the boat away. The part of 10 the oarlock carried by the oar is secured thereto and cannot fall off or be lost.

There can be no chance of the oar coming off the lock or the hub 7 slipping off the 15 pintle 5 while rowing, since the pin 12 secures these last named parts together.

The parts are few and simple and may be manufactured at small cost and are easily installed.

The invention has been put to extensive 20 actual usage and has been found highly efficient for the purposes above enumerated.

It will be understood that various changes 25 may be made in the form, details and arrangement of parts without departing from the scope of the invention.

What I claim is:—

1. In an oarlock, the combination with an 30 oar having a bearing extending transversely of its axis at its fulcrum point, of a substantially vertical pintle secured to the gunwale of a boat, a hub member journaled for horizontal pivotal motion on said pintle, and a substantially horizontal pin rigidly secured to said hub member adapted to pass 35 through the bearing in said oar and be secured thereto to permit vertical pivotal motion of said oar thereon.

2. In an oarlock, the combination with an 40 oar having a transverse aperture through the body thereof at its fulcrum point, of an upstanding pintle secured to the gunwale of a boat, a readily detachable hub member adapted to be journaled on said pintle for horizontal pivotal motion thereon, a substantially horizontal pin integral with said 45 hub and projecting therefrom passing through said aperture in said oar to permit vertical pivotal motion of said oar thereon,

an oar engaging flange on the inner end of said pin, and means engaging the outer end 50 of said pin to secure said oar thereon.

3. An oarlock, comprising an upstanding 55 pintle adapted to be secured to the gunwale of a boat, a hub member journaled for horizontal pivotal motion thereon, and means carried by said hub member nearer one end thereof than the other for securing an oar thereto with freedom for vertical pivotal motion, said hub member being reversible on said pintle whereby said oar may be set 60 to two different levels.

4. The structure set forth in claim 3, and a bushing disposed in the aperture in said oar forming a bearing for said pin.

5. An oarlock having in combination a 65 pivot member adapted to be secured to the gunwale of a boat, a co-operating pivot member mounted for horizontal pivotal motion on said first mentioned pivot member and means carried by said second mentioned pivot member nearer one end thereof than the other for securing an oar thereto with freedom for pivotal vertical motion, said second mentioned pivot member being reversible on said first mentioned member 70 whereby said oar may be set to two different levels.

6. In an oarlock, the combination with an 75 oar having a transverse aperture through the body thereof at its fulcrum point, of an upstanding pintle secured to the gunwale of a boat, a detachable hub member adapted to be journaled on said pintle for horizontal pivotal motion, a substantially horizontal pin carried by said hub member and projecting therefrom passing through said aperture in said oar and having a flange adjacent its inner end and adapted to engage one side of said oar and a bushing also passing through said aperture in said oar and surrounding said pin having a flanged head 80 adapted to engage the outer side of said oar.

In testimony whereof I affix my signature.

OLAF BERG.
